UNITED STATES PATENT OFFICE.

ANDREW CHRISTIANSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

CAR-DOOR MECHANISM.

1,121,164.

Specification of Letters Patent. Patented Dec. 15, 1914.

Application filed February 21, 1914. Serial No. 820,368.

To all whom it may concern:

Be it known that I, ANDREW CHRISTIANSON, a citizen of the United States, and resident of Butler, in the county of Butler and State of Pennsylvania, have invented a new and useful Improvement in Car-Door Mechanism; and I do hereby declare the following to be a full, clear, and exact description thereof.

10 My invention relates to a door mechanism for cars.

The invention relates more particularly to that class of door operating mechanism employed in connection with hopper bottom cars in which the sheaves and other operating parts are contained within the space formed between the inside hopper sheets between the hoppers which extend down on each side thereof.

20 The object of the present invention is to provide a strong and durable means for securing arms to the doors, in that type of locking mechanism where the arms are adapted to hook up over the end of a cam projection on the sheave, and drawn up into this position by means of chains.

To these ends my invention comprises novel features hereinafter set forth and claimed.

30 In the accompanying drawings, Figure 1 shows a side view of a portion of a hopper car with a portion of the hopper sheet removed and the means for connecting the operating mechanism to the door is shown in section. Fig. 2 is a like view showing the doors open, and Fig. 3 is a section on the line 3—3, Fig. 1. Figs. 4 and 5 are enlarged details.

In the drawing, the numeral 2 designates 40 the sides of the car to which the outside hopper sheets 3 are secured. The central sills 4 have the inside hopper sheets 5 secured thereto and said hopper sheets form the chamber 6 within which the operating parts for lifting the doors are contained. The shaft 7 extends transversely of the car and mounted on said shaft is the drum 8. A drum 9 is supported by trunnions 11 on brackets 12 secured to the center-sills and said drum has the sheaves 13. Chains 14 are secured to the drum 8 and pass around the sheaves 14 to which they are secured. This gives greater flexibility, and permits of the winding up of the links on the sheave 55 more readily.

The drum 9 has the cam portion 15 and the lug 16. A link 17 is connected to the lug 16, and a link 18 to said link 17.

The outer end of the shaft 7 is square and the ratchet-wheel 7^a engages said squared portion of said shaft. The ratchet-wheel 7^a is held on said shaft by the projection 7^b on the bracket 7^c. This bracket 7^c is riveted to the carbody and also forms a support for the pawl 7^d. The shaft 7 can 65 be withdrawn through the ratchet-wheel 7^a so said ratchet is held by the projection 7^b. This does away with the securing of the ratchet in place by a pin or other key. The hook-shaped arms 19 are connected to the 70 link 18 and when the door is closed the hooked portions of said arms 19 are adapted to engage the cam-portion 15 of the sheave 9 as clearly indicated in Fig. 1. The doors 20 are hinged as at 21 to the hopper-bottom, 75 and said doors are connected to the arms 19 by the bolts 22, the small links 23 being interposed between said bolts and said arms 19. The bolts 22 have their heads flattened to pass between the links 23 and the pin 24 80 passes through said links and bolt and is secured in place by the cotter-pin 25.

The pair of doors 20 are connected by the bar 26, which enables the pair of doors on opposite sides of the center-sills to be 85 operated simultaneously by the same operating mechanism. Secured to the bar 26 is the socket-plate 27, provided with the socket 28, said socket embracing a large portion of said bolt and well up to the upper end of 90 the bolt, so as to protect the same, and relieve the strain on the bolt thereby preventing bending or distorting of the same. The bolt 22 extends through the socket and a nut 29 engages the threaded portion of said 95 bolt, said nut entering an opening 30 in the bar 26, whereby said nut is locked against inward or outward movement on the nut. In order to change the position of the bolt 22, the bolt is disconnected from the link 23 100 by removing the cotter-pin 25 and the pin 24, whereupon the bolt may be adjusted by holding the nut 29 and turning the bolt, and the bolt is then connected up to the link 23. By this construction, the bolt, when 105 once adjusted, remains in this adjusted position, due to the fact that the nut 29 is held against longitudinal movement by its engagement with the opening 30 in the bar 26 and consequently, when the bolt is once 110

adjusted to bring the doors all into tightly closed position, there is no chance of the nut working loose to affect the adjustment after it has once been made. In this manner a tightly closed door can always be obtained. Furthermore, the bolt being protected by being inclosed by the socket well up toward its upper end, is relieved from strain and the bending which is liable to result therefrom.

What I claim is:

1. In a car, the combination with a downwardly swinging door, a socket carried by said door, a bolt engaging said socket, connections between said bolt and the door, lifting means, a nut on said bolt, and an extension on said door having an opening therein to receive said nut.
2. In a car, the combination of the pairs of doors, a bar connecting said doors having an opening therein, a socket on said bar, a bolt engaging said socket, a nut on said

bolt engaging said opening in said bar, and connections between said bolt and the door operating mechanism.

3. In a car, the combination with the pairs of doors, of a bar connecting the same, having an opening therein, a socket plate secured to said bar, a bolt engaging the socket in said plate, a nut on said bolt engaging said opening, and connections between said bolt and the door opening mechanism.

4. In a car, the combination of a door, an operating shaft having a square-end, a ratchet-wheel on said square-end, and a bracket on the car-body having a projection extending up in front of said ratchet-wheel.

In testimony whereof, I the said ANDREW CHRISTIANSON, have hereunto set my hand.

ANDREW CHRISTIANSON.
